UNITED STATES PATENT OFFICE

DAVID P. ANDERSON, JR., OF PITTSBURGH, PENNSYLVANIA

BOTTING APPARATUS

Application filed October 16, 1929. Serial No. 400,051.

This invention relates to botting apparatus for closing the cinder notch tuyères of blast furnaces, and has for its object the provision of a novel form of supporting and operating mechanism for such apparatus.

The novel form of supporting and operating mechanism for the botting bar of this invention is adapted to move the bar into and out of the cinder notch tuyère by a horizontal movement and means is provided for jarring the bar when it is being withdrawn from the tuyère so as to loosen said bar.

In the drawings:

Figure 1 is an elevation partly in section showing my improved apparatus as applied for use on a blast furnace.

Figure 2 is a sectional elevation of the botting apparatus taken on the line II—II of Figure 1.

Referring more particularly to the drawings, the numeral 2 designates a section of the blast furnace wall having the cinder notch tuyère 3 therein including a monkey-cooler 4 and monkey 4.

A botting bar A is provided for removably closing the opening in the monkey-cooler 4 and comprises a hollow shank portion 5 terminating in a tapered head portion 6. The shank to the rear of the portion 5 is in the form of a solid bar 7 and terminates at its rear end in a striking head 8 adapted to receive sledge hammer blows in an emergency if the bar becomes stuck in the monkey-cooler.

The hollow bar portion 5 and head 6 are formed hollow so as to permit water cooling, when desired.

The bar A is adapted to be supported by suitable operating mechanism which is carried by an overhead supporting plate 9. The plate 9 is supported by angle brackets 10 mounted on the bustle pipe 12 and bosh bands 13 of the furnace.

A pair of horizontally spaced and parallel links 14 and 15 are pivotally mounted in the same vertical plane on the plate 9. A pair of duplicate, curved guide tracks 16 and 17 are mounted on said plate 9 below said links. The tracks 16 and 17 are also spaced horizontally and aligned vertically.

A pair of connecting rods 18 and 19 are provided and one end of said rods is pivotally suspended from each of the respective links 14 and 15.

The lower ends of the connecting rods 18 and 19 are pivotally connected at horizontally spaced points to the solid bar portion 7 of the botting bar A.

The connecting rods 18 and 19 are provided with rollers 20 and 21, respectively, which are adapted to ride in the guide tracks 16 and 17, respectively.

The rollers 20 and 21 are so positioned on the rods 18 and 19 that they will maintain the links 14 and 15 in an upwardly and rearwardly inclined position. The tracks 16 and 17 are curved in such a manner as to guide the connecting rods 18 and 19 through a path when swung to and from said cinder notch tuyère as will maintain said bar in a horizontal position, and also to maintain said bar in a fixed horizontal plane when entering and moving out of said tuyère.

Due to the path of travel of the rods 18 and 19 caused by the tracks 16 and 17, the links 14 and 15 will be forced to swing about their pivotal mounting on the overhead plate 9 so as to form a vertically movable pivot point for said connecting rods.

A guide bar 25 is arranged in parallel spaced relation to the plate 9 and is secured thereto. The connecting rods 18 and 19 are passed upwardly through the space between the bar 25 and plate 9 and are thereby limited in their movement in a direction transversely of the plate so as to prevent displacement of the rollers 20 and 21 from the tracks.

In order to move the botting bar out of the tuyère a crank-shaped lever 26 is pivotally mounted intermediate its ends, as at 27, on the rearmost connecting rod 18, and a cable 28 has one end connected to the rear leg of lever 26 and its other end is trained upwardly over suitable sheaves and is secured to a winch 29.

When it is desired to withdraw the botting bar the winch 29 will be operated to take up the cable 28. The winch will be easily operated until the slack is taken up in the cable 28 and the lever 26 is rocked about its mount-

ing. Therefore, considerable speed may be developed by the winch. The pull on the lever 26 as the slack is taken out of the cable 28 will cause said lever to rock about its pivotal mounting and strike the rearmost connecting rod so as to jar the botting bar and loosen said bar if it is stuck in the tuyère.

When it is desired to insert the botting bar after it has been withdrawn from the tuyère the winch 29 is released and the bar descends 10 into the tuyère by gravity.

It will be understood that I do not wish to be limited to the use of the winch 29 for operating the cable 28 since various mechanisms may be substituted therefor.

While I have shown and described one specific embodiment of my invention I do not wish to be limited thereto since various modifications may be made without departing 15 from the scope of my invention, as defined in the appended claims.

I claim:

1. The combination with a cinder notch tuyère, of a botting bar adapted to close said tuyère, an overhead support, a pair of horizontally spaced and parallel links pivotally mounted in the same vertical plane on said support, a pair of curved guide tracks on said support, a pair of connecting rods having 20 their upper ends pivotally connected to the free ends of respective ones of said links and having their lower ends pivotally connected to said botting bar at horizontally spaced points, guide-rollers on said connecting rods and mounted to travel on said tracks, said 25 rollers being so positioned vertically on said rods as to maintain said links in an upwardly and rearwardly inclined position, and said tracks being curved so as to guide said connecting rods through a path when swung to and from said cinder notch tuyère as will maintain said bar in a horizontal position, said links moving about their pivotal mounting on said overhead support as said connecting rods are moved toward and away from 30 said tuyère and thereby forming a vertically movable pivot point for said connecting rods, means for limiting the movement of said connecting rods in a direction transversely of said tracks to thereby prevent displacement of said rollers from said tracks, means 35 connected to the rearmost one of said connecting rods for pulling said botting bar rearwardly, and means operated by said pulling means 40 for striking a blow against said rearmost connecting rod at the beginning of the pulling action.

2. The combination with a cinder notch tuyère, of a botting bar adapted to close said tuyère, an overhead support, a pair of horizontally spaced and parallel links pivotally mounted in the same vertical plane on said support, a pair of curved guide tracks on said support, a pair of connecting rods having 45 their upper ends pivotally connected to the

free ends of respective ones of said links and having their lower ends pivotally connected to said botting bar at horizontally spaced points, guide-rollers on said connecting rods and mounted to travel on said tracks, said 70 rollers being so positioned vertically on said rods as to maintain said links in an upwardly and rearwardly inclined position, and said tracks being curved so as to guide said connecting rods through a path when swung to 75 and from said cinder notch tuyère as will maintain said bar in a horizontal position, said links moving about their pivotal mounting on said overhead support as said connecting rods are moved toward and away from 80 said tuyère and thereby forming a vertically movable pivot point for said connecting rods, means for limiting the movement of said connecting rods in a direction transversely of said tracks to thereby prevent displacement of said rollers from said tracks, a 85 crank-shaped striking lever pivotally mounted on the rearmost one of said connecting rods, a drum, a flexible member connected to said drum and said striking lever adapted to be wrapped on said drum to move said botting bar from said tuyère and to be unwrapped from said drum to permit said botting bar to move by gravity into said tuyère, said flexible member being adapted to rock 90 said striking lever when said flexible member is wrapped on said drum so as to cause said lever to strike said bar and jar said botting bar to loosen it from said tuyère.

3. In a botting bar structure an overhead 100 support, a pair of connecting rods depending from said support, a botting bar connected to said rods, a crank-shaped striking lever pivotally mounted on one of said connecting rods, a flexible member connected to said 105 striking lever and adapted to be taken up to move said botting bar out of operative position and to be slackened to permit said botting bar to move by gravity into operative position, said flexible member being adapted 110 to rock said striking lever when said flexible member is taken up so as to cause said lever to strike said bar and jar said botting bar.

In testimony whereof, I have hereunto set 115 my hand.

DAVID P. ANDERSON, JR.
